AERIAL CARRIER FOR BOMBS OR THE LIKE

Filed April 21, 1942

UNITED STATES PATENT OFFICE

2,329,524

AERIAL CARRIER FOR BOMBS OR THE
LIKE

Thomas P. Duncan, Jr., Newport News, Va.

Application April 21, 1942, Serial No. 433,900

8 Claims.

(CL 102—6)

This invention relates to an aerial carrier for bombs or the like, and it is primarily an object of the invention to provide a device of this kind to be conveyed by the wind at a predetermined altitude, together with means comprised in the structure of the carrier for automatically allowing dropping of a bomb at an approximate predetermined period of time after the device has been freed for transit.

It is also an object of the invention to provide a device of this kind including a lighter-than-air member provided with means for coupling thereto a bomb or the like and wherein said member is provided with timed means for automatically releasing the bomb or the like for dropping at approximately a predetermined period of time after the member and its load has been put in transit.

The invention also has for a purpose to provide a carrier of this kind that can be readily released with its load from a ship, submarine, dirigible, captive balloon or land base at distances of from 25 miles to 600 miles or more from an objective and which carrier with its load will approach its objective silently and wherein the carrier is provided with means for releasing the bomb or the like therefrom with effective accuracy, whereby the carrier is particularly advantageous in use in attacking industrial centers, harvest crops, match box metropolises, etc.

An additional object of the invention is to provide a carrier of this kind including an inflatable balloon embodying a depending neck having means for coupling to a bomb or the like and wherein said neck at the time of release of the carrier or balloon with its load is provided with a charge to create such an erosion action to effect an automatic release of the bomb or the like from the carrier or balloon at an approximately predetermined period of time after the release of the carrier with its load.

A still further object of the invention is to provide a carrier of this kind including an inflatable body, together with a connector carried by the body for coupling a bomb or the like thereto, and wherein said connector is provided with means to permit the placing thereon of a dead weight equaling the amount of lift necessary to take the inflatable body and its load to a desired altitude, said weight being readily removable before the inflatable body with its load is released.

The invention consists in the details of construction and in the combination and arrange-

ment of the several parts of my improved aerial carrier for bombs or the like whereby certain important advantages are attained, as will be hereinafter more fully set forth.

5 In order that my invention may be better understood, I will now proceed to describe the same with reference to the accompanying drawing, wherein:

Figure 1 is an elevational view of an aerial carrier constructed in accordance with an embodiment of my invention and having a bomb coupled thereto.

Figure 2 is an enlarged detailed sectional view taken substantially on the line 2—2 of Figure 1, with parts in elevation, and

15 Figure 3 is a view in perspective of the connector as herein comprised, unapplied.

As disclosed in the accompanying drawing, B denotes an inflatable member or balloon bag of desired dimensions and which is adapted to be inflated by hydrogen or other suitable gas. The lower or free end portion of the neck 1 is closed by a cap or cup-like member 3 which tightly fits on the lower end portion of the neck 1 and is preferably adhesively held thereon.

20 The bottom or head 4 of this cap or member 3 is of material thickness and cemented to the inner face thereof is a plate or insert 2 of soft rubber which provides a soft rubber sealing seat. The head 4 of the cap member 3 is provided therethrough at its axial center with a tapered opening 5, the smaller end of which is innermost. The inner or smaller end of this opening 5 registers with an opening 6 in the plate or insert 2 of the head 4 and inserted from above through this opening 6 of the plate or insert 2 and extending within the opening 5 is an elongated tap or shank 7.

25 The tap or shank 7 is provided at its inner extremity, or that end portion of the tap or shank 7 within the neck 1, with an outstanding surrounding head 8 which has close contact with the inner face of the plate or head 2. This tap or shank 7 is of metal or other material eaten by an acid solution, such as a magnesium alloy or the well-known Dow metal, which is a metallurgical standard metal.

30 The outer end portion of the tap or shank 7 is provided axially thereof with an elongated socket 9 in which threads an end portion 10 of an elongated and substantially straight bar 11 comprised in the connector C. Threading on this portion 10 of the bar 11 is a nut 12 having contact with the outer face of a washer 14 surrounding the bar 11 and in direct contact with the

outer face of the head 4 of the cap member or cup 3. Upon turning the nut 12 in one direction around the bar 11, the head 8 of the tap or shank 7 will be pulled down into tight contact with the plate or head 2 which is preferably a relatively soft rubber fabric.

Fitted within the neck 1 of the bag B at a desired distance inwardly of the outer end of the neck is a plate 15 having disposed circumferentially therearound and rigid therewith a relatively broad flange 16 having close contact with the inner surface of the neck 1. This plate 15 and flange 16 are preferably of rubber material and the applied plate 15 with its flange 16 completely intersects the interior of the neck 1 whereby the chamber or cell 17 is provided between the plate 15 and the plate 2 to receive a charge 18 of a suitable acid, such as acetic acid.

The wall of the neck 1 and the flange 16 of the plate 15 are of such thickness and the material of such a character as to be self-sealing in connection with a small opening which may be produced therethrough. Initially the wall of the neck 1 and the flange 16 of the plate 15 below such plate 15 is pierced, as at 19, and which contracted and sealed opening 19 is readily located by a surrounding line 20 produced on the outer surface of the wall of the neck 1 and substantially concentric to this contracted opening 19, as is illustrated in Figure 1 of the drawing.

The chamber or cell 17 is preferably charged through the medium of a needle syringe and in the filling operation, the needle of such instrument is quickly inserted through the contracted opening 19. After the charge of the instrument has been emptied within the chamber or cell 17, the needle is withdrawn and the opening 19 will automatically seal as a result of the expansion of the wall of the neck 1 and of the flange 16.

The lower end of the bar 11 is returned to provide an elongated arm 21 provided at its free extremity with a laterally disposed open loop 22 straddling the bar 11. One of the side arms a of the loop 22 is extended to provide outwardly of the arm 21 an upwardly facing hook member 23 to provide means to allow for the suspension of a suitable weight for a purpose to be herein-after more particularly referred to.

The arm 21 and the bar 11 coact to provide a link whereby desired coupling may be had with an eye member 24 or the like at the tail end of a bomb A which may be incendiary, explosive or both. Insofar as the bomb A is concerned, it forms no particular part of the present invention. The arm 21 possesses a certain degree of inherent resiliency so that it may readily yield to allow the hook member 23, the members of the loop 22 and the arm 21 to readily thread therethrough when it is desired to couple the connector C to the bomb A.

Operatively connected with the wall of the neck 1 above the applied plate 15 and in communication with said neck above the plate 15 is an inflation valve V. As this valve V in itself forms no particular part of the present invention, it is not thought a detailed description thereof is necessary.

In practice, when the carrier with its bomb is to be released from a sea or land base, computations are made on a trial balloon for height and slip stream speed. After this determination, an acid solution of desired quantity is mixed from a suitable acid time chart and injected within the chamber or cell 17. However, before this injection or charging of the chamber or cell 17, the bomb A is run onto the connector C. A suitable

lift weight is suspended from the hook member 23 and the balloon bag B is inflated to zero lift. The lift weight is then removed and the balloon B with its load released. It is believed to be obvious that the use of a lift weight would be dispensed with when the balloon B with its load is released from dirigibles or captive balloons, already at the slip stream height.

From the foregoing description it is thought to be obvious that an aerial carrier for bombs or the like constructed in accordance with my invention is particularly well adapted for use by reason of the convenience and facility with which it may be assembled and operated.

What I claim is:

1. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, and means operatively engaged with said member for coupling a bomb or the like thereto, said last-named means including a part for suspending a lift weight.
2. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, and means operatively engaged with said member for coupling a bomb or the like thereto, said last-named means including a part for suspending a lift weight, the opening in the wall of the cell into which the member is received being outwardly flared to facilitate the passage of said member therethrough after the holding means has been eaten away.
3. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, a connector for coupling a bomb or the like to the balloon including a rod, and means for connecting an end portion of the rod to the member.
4. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, a connector for coupling a bomb or the like to the balloon including a rod, and means for connecting an end portion of the rod to the member, the opposite

end portion of the rod carrying a returned arm to facilitate the desired coupling of the connector to the bomb or the like.

5. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, a connector for coupling a bomb or the like to the balloon including a rod, means for connecting an end portion of the rod to the member, the opposite end portion of the rod carrying a returned arm to facilitate the desired coupling of the connector to the bomb or the like, and a part carried by said arm for suspending a lift weight.

6. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, a connector for coupling a bomb or the like to the balloon including a rod, and means for connecting an end portion of the rod to the member, the opposite end portion of the rod carrying a returned arm to facilitate the desired coupling of the connector to the bomb or the like, said arm being provided with a laterally disposed loop straddling the bar.

7. An aerial carrier for a bomb or the like comprising a balloon having a portion formed to provide an acid cell, a wall of said cell having an opening therethrough, a member freely disposed through said opening and having means coacting with the adjacent wall of the cell for initially holding the member in place, said holding means being of a material to be eaten away under the action of an acid charge within the cell to allow said member to drop out through the opening, a connector for coupling a bomb or the like to the balloon including a rod, means for connecting an end portion of the rod to the member, the opposite end portion of the rod carrying a returned arm to facilitate the desired coupling of the connector to the bomb or the like, said arm being provided with a laterally disposed loop straddling the bar, and a hook member carried by said loop for suspending a lift weight.

8. An aerial carrier for a bomb or the like comprising a balloon having a depending neck, an inflating valve for the balloon carried by a wall of said neck, a member intersecting the neck outwardly of the inflating valve to provide the neck with an acid cell, and means carried by the neck for suspending a bomb or the like from the balloon, said means including a part extending within the acid cell to be eaten away by the acid charge within the cell to release the bomb or the like, a portion of the wall of the cell having a filling opening disposed therethrough, said portion of the wall being of a material possessing sufficient inherent expansion to automatically maintain such opening closed.
